UNITED STATES PATENT OFFICE.

THOMAS E. MURRAY, OF BROOKLYN, AND JOHN H. LAWRENCE, OF NEW YORK, N. Y.;
SAID LAWRENCE ASSIGNOR TO SAID MURRAY.

BURNER.

Application filed April 22, 1925. Serial No. 24,922.

Our invention aims to provide an improved form of burner for boiler furnaces and similar furnaces using powdered coal, oil or gas or other fuel which is introduced 5 in jets.

In a previous Murray application Ser. No. 642,725, there is described a boiler, the furnace of which is surrounded by a water wall composed of vertical tubes spaced apart, 10 with overlapping flanges in the spaces so as to secure a wide exposure of heating surface in proportion to the volume of water circulating through the tubes; such boilers being designed for high pressure and for operating 15 at a very high rating, that is, generating steam in excessively large quantity per hour in proportion to the square feet of heating surface. Such operation is facilitated greatly by the exposure of the water wall de- 20 scribed to the direct radiant heat of the burning fuel. The burner of the present invention is particularly useful in connection with the furnaces of such boilers, being de- 25 signed to distribute the burning fuel throughout the combustion chamber to better effect than the ordinary burners.

The accompanying drawings illustrate em- bodiments of the invention.

Fig. 1 is a longitudinal vertical section 30 of a boiler and furnace with our improve- ment applied thereto;

Fig. 2 is a horizontal section of the same;

Fig. 3 is a section similar to Fig. 1 showing a modification.

Referring to the embodiments of the invention illustrated, the combustion chamber is surrounded by a water wall composed of vertical tubes 1 spaced apart with overlapping flanges 2 closing the spaces between 35 them and welded to the tubes as explained in the Murray application cited above. Out- side of this is a wall of sheet metal 3 and a layer 4 of insulating material. The outer wall may be of any other usual or suitable 40 construction. The vertical tubes described are connected at their lower ends to headers 5 and at their upper ends to headers 6 and are in communication with the regular cir- 45 culating system of the boiler. These tubes may be surmounted by additional sets of inclined tubes 7 connected at their ends to vertical headers 8 and 9 which in turn com- 50 municate with the steam drum 10. The side walls extend below the vertical tubes in the 55 form of supplementary walls 11 of fire-

brick or the like which extend also above the lower headers 5 and the lower ends of the tubes 1 so as to shield such headers and joints. The bottom of the furnace made of refractory material is indicated at 12 and at 60 the center of the floor and covering a large part of its area is the arrangement which as a whole we have referred to as the burner. A floor 13 of steel, concrete or other ma- 65 terial is located outside the refractory material.

Nozzles 15 are located in the central por- 70 tion of the concave or depressed portion of the floor, for introduction of a mixture of air and powdered coal and may be provided with a spiral rib 16 for causing a swirling motion and a better mixture of the air and coal. A screw feed for the coal and a com- 75 pressed air supply may be provided as usual in connection with powdered coal nozzles; such for example as are illustrated in Fig. 3. A number of nozzles 15 is arranged in line across the width of the furnace as indicated in dotted lines in Fig. 2. The concave por- 80 tion of the floor is provided with a lining 17 of refractory material; preferably openings 18 are provided in lines adjacent to the line of nozzles 15 for admitting a secondary sup- 85 ply of air. The lining 17 may be made of carborundum or other highly refractory bricks. For greater resistance to the heat there may be embedded in this lining water- 90 circulating tubes 19. These tubes are shown projecting in Fig. 2 with a number of return bends so that there is a continuous circula- 95 tion of water, entering through the pipe 20 and discharging through the pipe 21. Or several separate circulating pipes may be used.

Within the upper part of the concave 100 space defined by the lining 17 there is located a baffle 22 extending across and in line with the jets from the nozzles 15. The under surface of the baffle is depressed at the center with concave portions 23 at either side to divide the current and deflect it laterally against the concave lining 17, whence the mixed air and fuel pass sidewise and upward in two streams of wide cross-section into the combustion chamber where they spread 105 against the water walls at the sides and ends. Such a distribution of the flame is more ad- 110 vantageous in that it is spread over a wider area during the process of combustion and moves more slowly during this process than

the long narrow jets of flame proceeding from the ordinary nozzle burners.

Under certain conditions it may be desirable to admit a secondary supply of air near the point where the stream emerges into the combustion chamber. In that case ducts 24, 25 and 26 may be provided in the sides and bottom of the baffle through which air is forced by a blower to the furnace. These ducts are connected to a tubular passage 27 extending endwise through the baffle and communicating with supply pipes 28 (Fig. 2) at opposite ends. The baffle 22 may also be cooled by embedded pipes 29 extending longitudinally and connected as shown in Fig. 2 with an inlet pipe 30 and an outlet pipe 31. Instead of cooling the baffle and the liner 17 with water, air or other gases or other fluids may be used.

20 The burner is shown located in the bottom wall of the furnace. It may, however, be installed in any one of the side walls and a number of such burners may be installed in side walls or bottom wall or both. The burner may, if desired, be of other shapes than that illustrated.

While the invention is particularly advantageous in connection with a furnace lined with a water wall, because of the distribution of the radiant heat to such wall, it has advantages also in the regulated combustion and uniform mixture for other types of furnace. For example, in Fig. 3 we have shown such a burner applied in the bottom wall of a furnace having only ordinary side walls 32 of masonry. We have also in this figure shown the burner combined advantageously with the combined pulverizer and air mixer of a previous application which we have filed No. 700,214, Patent No. 1,614,314. In this case the coal 33 passes from a chute to a spiral conveyor 34 which feeds it at a regular rate to an air nozzle 35 through which air under pressure is continually forced. The mixture of air and coal strikes a breaking plate 36 with such velocity that at least a considerable percentage of the coal is broken so fine as to be carried along with the air current through the mouth 37 at the top of the casing which constitutes a nozzle similar to the nozzle 15 of Fig. 1. The pieces of coal which are so large as to drop out of the air current fall to the bottom of the casing and pass again to the screw conveyor 34 for a repetition of the breaking or pulverizing operation. By this means the current of air is used for the breaking of the coal and also for projecting it through the nozzle and for combustion after escape from the nozzle. The concave face of the burner is formed with a water cooled lining 17 similar to that of Fig. 1, except that in Fig. 3 it is shown

extending across substantially the full width of the furnace. A baffle 22 is located in line with the nozzle 37 and is similar in design and function to the baffle of Fig. 1.

Though we have described with great particularity of detail certain embodiments of our invention, yet it is not to be understood that the invention is restricted to the particular embodiments disclosed. Various modifications thereof may be made by those skilled in the art without departing from the invention as defined in the following claims.

What we claim is:

1. A furnace for burning powdered coal or the like comprising a main combustion chamber, a wall of the furnace being recessed, a nozzle for the fuel discharging at the back of said recess and a baffle in line with and beyond the mouth of the nozzle and forming with the recessed face of the wall a broad outlet passage which spreads the fuel into the main combustion chamber in the form of broad streams of flaming gas. 80

2. The furnace of claim 1, the baffle and recess extending continuously across practically the entire width of the wall so as to direct the fuel and air into the main combustion chamber in two streams at opposite sides of the baffle and of practically the entire width of the wall. 90

3. The furnace of claim 1 having water walls at the sides exposed to the direct radiant heat of the broad streams of flaming gas. 95

4. The furnace of claim 1, the recessed portion of the wall being provided with passages for the circulation of a cooling fluid. 100

5. A furnace for burning powdered coal or the like comprising a main combustion chamber having a bottom wall which is recessed, a nozzle for the fuel discharging at the back of said recess and a baffle in line with and beyond the mouth of the nozzle and forming with the recessed face of the wall a broad outlet passage which spreads the fuel into the main combustion chamber in the form of broad streams of flaming gas. 105

6. The furnace of claim 5, the baffle and recess extending continuously across practically the entire width of the wall so as to direct the fuel and air into the main combustion chamber in two streams at opposite sides of the baffle and of practically the entire width of the wall. 115

7. The furnace of claim 5 having upright water tubes at the sides of the chamber exposed to the radiant heat of the broad streams of flaming gas. 120

In witness whereof, we have hereunto signed our names.

THOMAS E. MURRAY.
JOHN H. LAWRENCE.
